PACKAGING TRAY

William D. Stockdale, Arlington Heights, Ill., assignor to Illinois Tool Works Inc., Chicago, Ill., a corporation of Delaware

Filed Feb. 7, 1967, Ser. No. 5,714

Term of patent 14 years

(Cl. D9—187)

FIG. 1 is a bottom plan view of a packaging tray showing my new design;

FIG. 2 is a side elevational view thereof;

FIG. 3 is an enlarged fragmentary bottom plan view as seen on lines 3—3 of FIG. 5;

FIG. 4 is an enlarged fragmentary view as seen on lines 4—4 of FIG. 5; and

FIG. 5 is an enlarged fragmentary side elevational view thereof.

I claim:

The ornamental design for a packaging tray, as shown.
